UNITED STATES PATENT OFFICE.

CHARLES F. GAUNT, OF BIRMINGHAM, ENGLAND.

MEDAL-RIBBON CARRIER.

1,413,468.

Specification of Letters Patent. Patented Apr. 18, 1922.

Application filed February 9, 1920. Serial No. 357,411.

To all whom it may concern:

Be it known that I, CHARLES FREDERICK GAUNT, of the city of Birmingham, England, a subject of the King of Great Britain, 5 have invented certain new and useful Improvements in Medal-Ribbon Carriers; and I do hereby declare that the following is a full, clear, and exact description thereof.

This invention has reference to medal 10 ribbon bars and medal bars.

Heretofore it has been proposed to construct medal ribbon bars in various ways so as to enable the medal ribbon to be fixed thereon without sewing and also provide a 15 ready means of securing the medal ribbon to a garment. My invention is of this class, and can be employed for securing together two or more full sized or miniature medal bars and attaching them to a garment.

20 My invention is chiefly applicable where it is required to fix two or more medal ribbons or medal bars to one bar or the like furnished with means for attaching it to a garment. According to my invention each 25 medal ribbon is mounted on its own independent short bar furnished with attachment means or constructed for its attachment, each thus forming an independent medal ribbon unit and one or more of these 30 independent medal ribbon units is or are removably fixed singly or in a row on a long back bar or the like which is furnished with means for its attachment to a garment.

It is intended that a military tailor for 35 instance would keep in stock a number of various kinds of these independent medal ribbon units and long back bars or the like so that it thus becomes a very simple matter for him to mount several medal ribbons on 40 one long back bar or the like whilst a customer waits, as all that is necessary is for him to affix to the front of the back bar or the like the required number and kinds of independent medal ribbon units which are 45 attached to the back bar or the like by screwed stems projecting at the back of the units passing through a slot or slots in the back bar or the like and secured by nuts at the back, or by the bars of the various medal 50 ribbon units being furnished with eyelets which pass through the slot or slots in the back bar and are clenched over washers on the back of the same.

In a similar manner I removably attach 55 to a long back bar or the like several full size medal bars or miniature medal bars.

For full comprehension, however, of my invention, reference must be had to the accompanying drawings in which similar reference characters indicate the same parts, 60 and wherein:

Figure 1 is an elevation of a medal ribbon bar constructed in accordance with my invention;

Figure 2 is a plan view thereof;

Figure 3 is a back elevation;

Figure 4 is a back view of the back plate removed and illustrating a modification of the slots;

Figure 5 is a detail view of one of the individual trough sections;

Figure 6 is a detail back view drawn to a larger scale of a portion of my improved medal ribbon bar;

Figure 7 is a transverse sectional view 75 taken on line 7—7 Figure 6;

Figure 8 is a similar view to Figure 6 of a modified construction;

Figure 9 is a sectional view taken on line 9—9 Figure 8; and

Figure 10 is a detail view of one of the attachment plates.

The particular medal ribbon bar shewn by Fig. 1 has three independent medal ribbon units marked respectively A, B and C 85 and these are removably fixed in a row on the long back bar D which is furnished with means for its attachment to a garment, the particular means in the example illustrated by my drawings being an ordinary brooch pin 1 which is jointed to the back bar at 2 and when fastened engages with the catch 3 fixed to the other end of the back bar. Each of these independent medal ribbon units is preferably constructed 90 as illustrated by Figs. 5, 7 and 9. Each unit comprises a flat, shallow, thin sheet metal bar of channel cross-section and its length is equal to the width of the medal ribbon and an attachment plate 8 located between 95 the side edges 5 and 6 of the channel member. These edges are bent back upon the attachment plate to clamp the ends of the ribbon therebetween and the channel bar 4, the ribbon being stretched over the front of 100 the latter with its ends positioned between the channel bar and plate.

The attachment plate 8 is furnished with suitable means for removably fixing it to the back bar D. This attachment means is 110 preferably in the form of a screw shank 9 which is fixed to the back plate 8 at the cen-

- ter of the same so as to project from the back of the same and pass through a longitudinal slot 10 in the back bar D and be there secured by a nut 11 screwed on to the shank 9. Another effective means for removably securing the short bar 8 to the back bar D is for the short bar 8 to be furnished at its centre with an outstanding eyelet 12 (see Figs. 8 and 9) soldered thereto and adapted to pass through the slot 10 of the back bar D and to be then clenched and spread over a washer 13 as in Fig. 8 at the back of the back bar D. The back bar D is preferably made of flat section and with parallel sides so as to fit against the short bar 8 in between the turned over ribbon covered edges 5, 6 which thus keep the independent medal ribbon units in position parallel with the back bar D and prevent them from getting askew thereon. The back bar D is preferably made slightly shorter than the width of the one, two, three or more medal ribbon units which it is required to hold and is made of the proper width to fit in the groove between the back turned ribbon covered edges 5, 6, of the medal ribbon units. The back bar D need not necessarily have a brooch pin for its attachment to the garment as it may for instance be made with eyes or holes at the ends for sewing on to the garment or be otherwise suitably formed so as to be attached thereto. The said back bar D is however preferably formed of a longitudinal parallel sided sheet metal blank pierced with a long slot 10 or with two or more short slots end to end or with a hole or two or more holes in a row for the screws or attachments to pass through as aforesaid.
- 40 It will be seen that when the medal ribbon bar is constructed as above described one or more independent medal ribbon units can be readily attached to the back bar D by being placed in position at the front of the back bar with the screw shank or eyelet or the like passing through the slot or hole in the back bar and there secured as by the nut screwed on to the shank and tightened up, or by the eyelet (see Figs. 8 and 9) passed through a washer and spread over on the back.

My invention as above described in con-

nexion with medal ribbon bars can be similarly applied to full sized medal bars or miniature medal bars by each of said medal bars having attached to the back of it a screw shank or an eyelet or other attachment means by which it is attached to a back bar such as D which is furnished with means for its attachment to a garment. 60

What I claim is as follows:

1. A medal ribbon carrier consisting of a unitary bar and a plurality of ribbon units detachably mounted thereon independently of each other, each unit consisting of a ribbon bar of channel cross-section and adapted to have a ribbon stretched thereon with its ends overlapping the side edges thereof, a plate located between the side edges of said channel bar and securing the overlapping ends of the ribbon upon said channel bar, the side edges of the latter being bent down upon and overlapping the plate and clamping the same and the ribbon in place, and means upon said plate for detachably fastening the same to the unitary bar. 70

2. A medal ribbon carrier consisting of a unitary bar and a plurality of ribbon units detachably mounted upon said bar independently of each other, each of said units consisting of a ribbon bar or channel cross-section, a plate located between the side edges of said ribbon bar, the bar being adapted to have a ribbon stretched thereon with the ends of the ribbon overlapping the side edges of the ribbon bar and interposed between the latter and the plate, the side edges of said bar being bent down upon and overlapping said plate for the purpose of cramping the same and the ribbon upon said ribbon bar, and means for detachably fastening each unit to the unitary bar, said means consisting of an opening in said unitary bar and a screw-threaded shank rigidly mounted upon said plate and extending through said opening, and a nut on said shank and means for fastening the carrier to a garment. 85

In testimony whereof I have signed my name to this specification in the presence of two witnesses.

CHARLES F. GAUNT.

Witnesses:

GORDON G. COOKE,

WILLIAM J. C. HEWETSON.

Certificate of Correction.

It is hereby certified that in Letters Patent No. 1,413,468, granted April 18, 1922, upon the application of Charles F. Gaunt, of Birmingham, England, for an improvement in "Medal-Ribbon Carriers," errors appear in the printed specification requiring correction as follows: Page 2, line 81, claim 2, for the word "or" read *of*, and line 89, for the word "cramping" read *clamping*; and that the said Letters Patent should be read with these corrections therein that the same may conform to the record of the case in the Patent Office.

Signed and sealed this 16th day of May, A. D., 1922.

[SEAL.]

KARL FENNING,

Acting Commissioner of Patents.
